CLAIM

The ornamental design for a jewelry clasp chain, as shown and described.

DESCRIPTION

FIG. 1 is a front isometric view showing my new design; FIG. 2 is a top plan view thereof; FIG. 3 is a bottom plan view thereof; FIG. 4 is a front side view thereof; FIG. 5 is a rear side view thereof; FIG. 6 is a left view thereof; FIG. 7 is a right side view thereof; FIG. 8 is an enlarged isometric view of the circled portion shown in FIG. 1; and, FIG. 9 is an enlarged top plan view of the circled portion shown in FIG. 2. The broken lines showing a necklace illustrate environmental structure that forms no part of the claimed design.
